PICTURE HANGER

Jens J. Krogh, Alpharetta, Ga., assignor of one-half to Brevard Williams, Atlanta, Ga.

Application December 10, 1949, Serial No. 132,266

2 Claims. (Cl. 248—28)

1

This invention relates to a picture hanger and more particularly to apparatus for hanging a picture in such a manner that the picture remains level even when jarred, but is readily movable laterally along a level line without the necessity of repositioning screws or the like on the supporting surface.

In the hanging of pictures on the walls of rooms, it is desirable that the pictures be properly located with respect to height and corner symmetry and that they remain level after positioning at the desired spot; but, as various changes are made in the room, such as the addition of furniture or mirrors, it often becomes necessary to shift the position of the picture laterally on the wall to maintain balance and symmetry in the room.

The more common apparatus for hanging pictures consists of a wire attached to the back of the picture frame for cooperation with a nail or screw driven into the wall, and when it becomes necessary to move the picture laterally it is necessary to remove the nail or screw and re-locate it at the desired new position. This practice is awkward and leaves the wall surface damaged and unattractive. Further, with this prior art arrangement, any jarring or shaking of the floor or the wall tilts the picture and it is necessary to be constantly releveling the picture.

The prior art picture hangers have not been adequate from many standpoints, such as simplicity of installation and dependency of operation, nor have they provided a structure which is readily marketable at an inexpensive level.

It is an object of this invention to provide a picture hanger which is readily adaptable to any size picture.

A further object of this invention is to provide a picture hanger which can be readily installed without the necessity of complex equipment or calculations.

Also an object of this invention resides in the particular arrangement whereby after the picture is installed it may be readily shifted laterally along a level line.

Another object of this invention is to provide a picture hanger which safely supports the weight of heavy pictures and the like on vertical surfaces.

A further object of this invention is to provide a picture hanger which retains the picture in a level position even with jarring or vibration of the supporting surface.

Another object of this invention is to provide a picture hanger which is completely concealed

behind the picture back and therefore not visible to viewers of the picture.

Another object of this invention is to provide a picture hanger which is easy and inexpensive to fabricate and market.

Other and further objects and advantages of my invention will be apparent from the following description taken in conjunction with the accompanying drawings in which like characters of reference designate corresponding parts throughout the several views, and wherein:

Fig. 1 is a front view of a detail of my invention.

Fig. 2 is a back view of a conventional picture frame with a further detail of my invention mounted thereon.

Fig. 3 is a perspective view of a picture mounted by my invention on a supporting surface.

Fig. 4 is an elevation of a detail.

Fig. 5 is a cross-sectional view taken along the line 5—5 of Fig. 3.

In the embodiment of my invention chosen for illustration, a flat, elongated support strip 10, of metal, plastic or other suitable material, has a plurality of holes 11 spaced substantially along the longitudinal center line and is designed to be removably attached to a wall 12, or other support, by means of a pair of special retaining screws 13, 13'.

As is readily seen in Fig. 4, the retaining screws have a long tapered shank 14 with wide spiral threads, for gripping plaster especially, and an enlarged shoulder portion 15 near the grooved head 16. Screw 13' has a similar shoulder 15'. The shoulder portions 15, 15' are larger than the openings 11 in the support strip 10 so that the shoulders 15, 15' protrude outwardly from the strip 10 when the strip is tightly screwed to the wall 12 by screws 13, 13', as is readily seen in Fig. 5.

A flat, elongated attaching strip 17, likewise of metal, plastic or other suitable material, has a series of longitudinally spaced holes 18 near the upper edge thereof and a series of longitudinally spaced serrations or notches 19 on the bottom edge thereof. Strip 17 is attached to a picture 20 on the opposite vertical sides of the conventional picture frame 21 by means of a pair of screws 22 passing through a spaced pair of the openings 18. The serrations 19 are slightly larger than the shoulders 15, 15' of screws 13, 13' so that the attaching plate 17 may be readily hung on the shoulders 15, 15' of screws 13, 13', respectively, with a sliding fit.

When hanging a picture by my invention, the

strip 10, of the appropriate size according to the picture width, is located properly with respect to the room and carefully leveled with respect to the surface of the floor and ceiling, and then the two special screws 13 and 13' are screwed into the wall 12 through a pair of the openings 11 in the strip 10 thereby securing the supporting strip 10 to the wall 12. In this position the enlarged circular shoulders 15, 15' of the screws 13, 13', respectively, protrude outwardly from the plate 10 to form in effect a pair of wall pins, and the special screws 13, 13' enter deeply and securely into the wall 12 thereby providing a rigid support. Then the attaching strip 17, cut to appropriate length, is secured to the back of the vertical side moulding 21 of the picture 20 by means of the screws 22 which pass through a pair of spaced holes 18 that are in alignment with the moulding 21. In placing the strip 17 on the picture moulding, the upper edge may be leveled with respect to the upper margin of the picture 20 thereby assuring proper leveling when placed on the wall. As is readily seen in Fig. 3, the picture 20 is hung in place on wall 12 by aligning one of the serrations 19 over the protruding enlarged shoulder 15 of the screw 13, and at the same time the other spaced screw 13' will come into alignment with another one of the serrations 19 so that the attaching strip 17 with the picture may be lowered until the upper inside surface of the serrations 19 support the weight of the picture on the screws 13, 13'.

After the picture is in position, the shoulders 15, 15' of the two screws 13, 13' provide a two-point support spaced longitudinally of the picture 20 so that any jarring or vibration of the wall 12 will not disturb the level position of the picture 20; however, if it becomes desirable to relocate the picture laterally of the wall surface 12, that is, toward one or the other corners of the room, then the serrations 19 are dis-engaged from the screws 13, 13' by lifting upwardly on the picture 20. The picture 20 is moved laterally the desired distance and then lowered so that a different pair of serrations 19 match up with the shoulders 15, 15' of the screws 13, 13'. Of course, more than two of the screws 13 may be used in hanging a picture, and because the strip 10 acts as a template the screws 13 will always match with a serration 19 in the strip 17.

In marketing my picture hanger, the support strip 10 and the attaching strip 17 may be supplied in continuous lengths which may be rolled and packaged. With this arrangement, the required amount of support strip 10 and the required amount of attaching strip 17 may be fitted to the particular frame and then cut from the continuous lengths. This also permits simple fabrication of my picture hanger since the continuous lengths of the support strip 10 and the attaching strip 17 may be machine formed from continuous lengths of flat metal or plastic or other suitable material.

It is not necessary in positioning the components of my picture hanger to have the two screws 13, 13' exactly the same distance from the side edges 21 of the picture 20 and with this ad-

vantage a larger or a smaller picture frame may be substituted for the one presently in use. The entire structure is concealed behind the picture and retains the picture on the wall in an attractive manner.

It is obvious that I have presented a needed article of great utility and although I have illustrated a preferred embodiment thereof, it will be apparent to those skilled in the art that many modifications and changes may be made in the embodiment shown and described without departing from the scope of my invention as defined in the appended claims.

I claim:

15. 1. In apparatus of the class described, an elongated strip having a plurality of longitudinally spaced holes therethrough, a plurality of retaining screws cooperating with said holes for attaching said strip to a supporting surface, each of said screws having a threaded shank inserted through one of said holes and a shoulder portion larger than said holes, an attaching strip having a plurality of notches longitudinally spaced along the bottom edge thereof, said notches being spaced apart the same distance as the holes in said elongated strip, and means for attaching said attaching strip to an article to be supported, certain of said notches cooperating with said screws for removably supporting said article on said supporting surface.

2. In apparatus of the class described an elongated strip having a plurality of spaced holes substantially along the longitudinally center line thereof, a plurality of retaining screws cooperating with said holes for attaching said strip to a supporting surface, each of said screws having a threaded shank smaller than said holes and a shoulder portion larger than said holes, said shoulder portion protruding from said strip when said strip is fastened to a supporting surface by means of said screws, an attaching strip having a plurality of holes longitudinally spaced adjacent the top edge thereof and a plurality of serrations longitudinally spaced along the bottom edge thereof, said serrations being spaced apart the same distance as the holes in said elongated strip, and means cooperating with certain of said holes in said attaching strip for attaching said attaching strip to an article to be supported, certain of said serrations cooperating with the shoulder portion of said screws for removably supporting said article on said supporting surface.

JENS I. KROGH.
